UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,157,276.

Specification of Letters Patent.

Patented Oct. 19, 1915.

Application filed April 29, 1913. Serial No. 764,300.

To all whom it may concern:

Be it known that I, CLIO B. YAW, citizen of the United States, and resident of Arlington, in the county of Hudson and State 5 of New Jersey, have invented certain new and useful Improvements in Type-Writing Machines, of which the following is a specification.

My invention relates to paper cutting and 10 controlling devices for typewriting machines and its object is to provide new and improved devices of the character specified, the novel devices being especially useful in systematically cutting short strips or sections from a continuous roll or web although of course not restricted to such use.

To the above and other ends my invention consists in the features of construction, combinations of devices and arrangements of 20 parts hereinafter described and particularly pointed out in the claims.

My invention is applicable to typewriting machines generally, but the preferred embodiment herein illustrated has been applied to a No. 10 Remington typewriting machine as shown in the accompanying drawings, wherein—

Figure 1 is a fragmentary end view, partly in section, of the upper portion of a 30 No. 10 front strike Remington typewriting machine embodying my invention. Fig. 2 is a fragmentary plan view of the same. Fig. 3 is an enlarged transverse sectional view taken on a plane indicated by the dotted line z in Fig. 2, the pivotal cutting blade being shown moved to a position to partially cut the paper.

The main frame of the machine comprises 40 posts 1 supporting a top plate 2 above which are secured grooved guide rails 3 which cooperate through anti-friction balls 4 with the grooved front and rear bars, numbered respectively 5 and 6, of a truck which further comprises end bars 7. Supported on 45 the truck is a platen frame comprising end bars 8, said end bars being connected by cross bars or rods of which the rearmost two are illustrated and numbered 9 and 10. The traveling platen carriage or carrier 50 comprises said truck and said platen frame, said frame pivotally supporting a platen 11 and being shiftable up and down on the truck to change case, although in the present instance I prefer to set the platen frame 55 in fixed relationship with the truck, as in the

special character of work for which the present invention is more particularly designed, only upper case types are employed. Operatively connected with the right-hand end of the platen 11 is a line spacing 60 ratchet wheel 12 with which co-operates a spring mounted roller detent 13. Line spacing movements are communicated to the platen by devices comprising a pawl 14 pivoted on an arm 15 which in turn is pivoted 65 to swing about the platen axle 16, as an axis, said pawl being operative by a train of devices comprising a link 17 which connects it with a bell crank 18, said bell crank being connected by a link 19 with a crank arm 20 70 on a rock shaft 21 which turns in a housing 22 mounted on the carriage truck. The rock shaft terminates in a downwardly extending handle or finger piece 23 which is operative to actuate said pawl 14 to line space 75 the platen and also concurrently to restore the carriage from left to right to begin a new line of writing.

Mounted on the carriage is a paper supply 80 roller or spool that comprises both a core or axle portion terminating in reduced end portions 24 and also flanges or end pieces 25 mounted on the core, the paper indicated in the present instance by the numeral 26 being wound on the core and confined between 85 the flanges. The supply roller is mounted on a support or frame comprising parallel end bars or arms 27 and a connecting cross bar 28, the upper ends of the arms 27 being slotted as indicated at 29 to receive the end 90 or bearing portions 24 of the supply roller. The arms 27 are formed with holes through which the rod 9 of the platen frame passes and at their lower ends said arms are slotted, as indicated at 30, to co-operate with the 95 frame rod 10. The support or frame comprising the arms 27 is adjustable lengthwise of the platen, being confined between adjustable collars 31 which are set on the rod 9. The paper 26 is drawn off from the 100 supply roller at the rear side and led around and up at the front side of the platen to the severing devices hereinafter described, which are arranged above the platen. A friction spring 25^a secured to one of the 105 arms 27 co-operates with the adjacent flange 25 to prevent undue rotation of the supply roller. Between the severing devices and the supply roller or spool, paper guiding devices are arranged, said devices including 110

a guide bar 32 which is adjustably mounted on the arms 27, said bar 32 being slotted near its ends as indicated at 33, the slots receiving clamping screws 34 which screw into the arms 27, the construction affording an adjustment of the bar 32 lengthwise of the platen. Mounted on the bar are marginal guiding devices or lips 35 which extend inward toward each other, the paper 10 passing over said bar and under said marginal devices 35, which latter may, if desired, be the inturned end portions of a separate piece suitably secured to the bar 32.

The paper shearing or severing devices or 15 elements are mounted on a support or bar 36 which in turn is mounted on the carriage or carrier, being secured to the end bars 7 of the truck. The bar 36 extends longitudinally of the platen and is arranged above 20 the platen and forward thereof. In order to position the bar in the desired location it is mounted on short posts 37 arranged in pairs on the end bars 7 and each threaded at its upper end, as indicated at 38, to receive 25 pairs of nuts 39 between which the bar 36 is clamped at its end portions. As is apparent the construction is such that the vertical position of the support or bar 36 may be varied by adjusting the nuts 39 on the threaded portions of the posts 37, thus 30 varying the position of both the bar and the cutting devices mounted on it in respect of the printing line on the platen. At its right-hand end the bar 36 is offset forward, as indicated at 36^a, so as not to interfere with 35 the line spacing mechanism. Secured to the upper face of the bar 36 in fixed relationship therewith by screws 40 is a severing member, device or blade 41, said blade extending 40 along said bar with its sharpened or cutting edge at the rear side. A co-operating cutting device, member or blade 42 is pivotally supported above the rigid or relatively fixed blade 41, said swinging or 45 pivotal blade being pivoted on a shouldered screw or other suitable pivot 43 at or near its left-hand end, which pivot screws into and if desired through the underlying blade. Normally the blade 42 is swung rearward to 50 the position shown clearly in Fig. 2, its cutting or sharpened edge being at the forward side facing the cutting edge of the rigid blade 41. When the blade 42 is thus disposed, the paper may pass upward between 55 the blades 41 and 42 after it has been printed on by the co-operation of the types (not shown) with the front or printing face of the platen. The rearward swinging movement of the blade 42 is limited by a lug 60 or stop device 44 fixed to the bar 36 and co-operating with an inclined stop face 45 on the tail or rear portion of the blade. The stop devices 44 and 45 are normally maintained in engagement by spring means comprising a coiled spring 46, one end of which 65 is anchored to a pin 47 on the bar 36, the other end being hooked over a pin 48 on a finger or projection 49 which extends rearwardly from the blade at substantially right angles thereto. The tail portion of 70 the blade 42 is provided also with a stop face 50 oppositely inclined from the face 45 and co-operative with a stop device or lip 51 which is preferably turned up from the left-hand end of the blade 41. This stop 75 device 51 co-operates with the stop face 50 to limit the forward swing of the blade 42 and prevent excess movement in the cutting or operative direction. The pivotally connected blades 41 and 42 are adapted to receive 80 relative swinging or pivotal movement with respect to each other, this movement in the present instance being brought about by swinging the blade 42 on its pivot by means operating automatically during the 85 travel of the carriage, and preferably at a predetermined point in the return movement of said carriage. The automatic devices comprise a finger 52 extending forward from the blade 42 and at substantially right 90 angles thereto, said finger being adapted to co-operate with a stationary device, abutment or pin 53 which is secured to the free end of an arm 54, said arm being secured to the left-hand side of the top plate 2 by 95 screws 55 and extending inward toward the middle of the machine therefrom. The pin 53 extends upward so that it intersects the path of the finger or projection 52 and when in the course of return movements of the 100 carriage, said projection engages said finger, the spring 46 will be overcome and the blade 42 will swing forward in a substantially horizontal plane co-acting with the blade 41 to shear or sever the paper which passes between them. 105

In order properly to guide the paper upward between the blades guiding devices are provided which guide the paper after it leaves the printing point in a plane which is substantially at right angles to the plane in which the relative movement between the blades 41 and 42 takes place. In other words, the plane of the paper in the neighborhood of the line of severance is substantially vertical while the plane in which the blade 42 swings is substantially horizontal. Said guiding device comprises a short vertically disposed chute or guide 56 having a forwardly extending lip 57 secured by 110 screws 58 to the under side of the bar 36, the chute extending downward nearly vertically from said bar and substantially in line with the printing face of the platen and terminating a short distance above the 115 printing line so that the paper passes into said chute or guide shortly after being printed on and leaves the chute at the top just prior to intersecting the path of the cutting blade 42. 120

130

The invention is particularly designed for use in severing short slips or strips from the roll or web of paper, said strips in the present instance each containing a single line of writing, and to facilitate the work, a receptacle, container or holder is provided for receiving the printed slips and means connected with the severing devices are provided for moving the printed slips after they have been cut, out of the way transversely of the unsevered paper and into the receptacle or container. The paper moving means in the present instance comprises an abutment, blade or lip 59 which is turned upward at right angles from the body portion 60 that is secured by screws 61 to the top of the blade 42. The moving device or means 59 extends longitudinally of the blade 42 and is arranged above its cutting edge and nearly in the plane thereof so that as the paper is cut during the cutting stroke of the blade 42 by the coöperation of its edge with the blade 41, the severed or cut strip or slip will be pushed forward by the abutment or device 59 and into the receptacle indicated as a whole as 62. This receptacle preferably is an open frame of sheet metal mounted on the bar 36 and comprising a horizontal portion 63 secured by the screws 58 to the under side of said bar below the lip 57. From the forward side of the horizontal portion the receptacle is bent upward to provide a front wall 64 terminating in rearwardly inclined lips 65, side lips or lugs 66 also being provided to prevent endwise displacement of the paper slips during movements of the carriage. The vertical wall 64 is cut down as indicated at 67 so as to facilitate the removal by hand of the accumulated slips from the receptacle. These slips, it will be understood, after they have been pushed one by one by the device 59 over the upper face of the blade 41 will drop down below the forward edge of said blade which is cut out as indicated at 41^a so as to provide in connection with the front face of the bar 36 a low, rear wall or face for the receptacle.

As will best be understood from Fig. 3 the slips are supported in the receptacle on the bottom face 63 and between the face 41^a and the wall 64. In said Fig. 3 the uncut portion of the paper extending upward through the chute 56 is omitted for the sake of clearness. The parts are so arranged that the paper web is cut midway between successive single line entries printed on it and it will be understood that after one line has been written the paper is line spaced and the carriage is drawn backward and during the backward or restoring movement of the carriage the device 52 will coöperate with the abutment 53 to swing the blade 42 forward, thereby giving it a cutting stroke and causing it to coöperate with the blade

41 to shear the paper below the uppermost entry thereon while concurrently the severed slip containing this uppermost entry will be pushed or moved forward out of the way by the device 59 and into the receptacle 76 62. The parts are arranged so that the severing movement or cutting stroke will be completed when the carriage reaches its limit of rightward movement. Thereafter as the carriage moves leftward during 75 printing operations the blade 42 will be gradually swung back to normal position by the spring 46 which, of course, has been overcome and extended during the shearing operation.

My present invention is simple and inexpensive in construction, containing few parts and operates automatically to sever the work sheet periodically and systematically into convenient lengths or slips, 85 also gathering these slips in order in a receptacle, receiver or container for convenient handling. By providing for a shearing cut I insure that the paper shall be severed cleanly, avoiding ragged edges and an obstruction of the operation which might occur as the result of imperfect cutting.

Various changes may be made without departing from the spirit and scope of my invention.

What I claim as new and desire to secure by Letters Patent, is:—

1. In a typewriting machine, the combination of two coöperating paper shearing elements, and means operating automatically 100 at will to effect relative movement of said elements transversely of the plane of the paper, the paper being severed during and by reason of such automatically effected transverse movement.

2. In a typewriting machine, the combination of a traveling platen carriage, two relatively movable paper shearing elements both mounted on said carriage, and means operating automatically at will to effect relative movements between said elements transversely of the platen to sever the paper.

3. In a typewriting machine, the combination of a traveling platen carriage, two relatively movable paper shearing elements both mounted on said carriage, and means for effecting relative movements between said elements transversely of the platen to sever the paper, said means operating automatically during the carriage travel and being 120 rendered effective thereby.

4. In a typewriting machine, the combination of a traveling platen carriage, two elements relatively movable transversely of the platen to shear paper, and means operating 125 automatically during traveling movements of the carriage to effect such relative movement, the operation of said automatic means being due solely to the traveling movements of the carriage.

5. In a typewriting machine, the combination of a traveling platen paper carriage, two elements relatively movable transversely of the platen to cut paper supported on said carriage, and means including a stationary device operating automatically to effect such relative movement during traveling movements of the carriage.

6. In a typewriting machine, the combination of a traveling platen carriage, two elements relatively movable transversely of the platen to shear paper, said elements being mounted on the carriage, and automatic means including a stationary device for 15 effecting such relative movement.

7. In a typewriting machine, the combination of two paper shearing elements mounted for relative swinging movement about a pivotal axis, and means operating automatically to effect such pivotal movement, the paper being sheared by the coöperation of said elements while said relative swinging movement is taking place.

8. In a typewriting machine, the combination of a traveling element, a frame element, two coöperating paper shearing devices both mounted on a single one of said elements, and means operating automatically to cause said devices to co-act to sever the paper at will by a shearing movement transversely of the direction of travel of said traveling element.

9. In a typewriting machine, the combination of a traveling element, a frame element, two coöperating paper shearing devices both mounted on a single one of said elements, and means operating automatically to cause said devices to co-act to sever the paper at will, said co-action taking place during traveling movements of said traveling element and causing the paper to be sheared by a movement transverse of the direction of such traveling movements.

10. In a typewriting machine, the combination of two pivotally connected paper cutting blades capable of relative swinging movement during which the paper between said blades is sheared, and automatic means for causing such relative movement whenever desired.

11. In a typewriting machine, the combination of a traveling carriage, two cutting blades supported on said carriage, said blades being pivotally connected, and means 55 operative to cause said blades to swing relatively to shear the paper during traveling movements of said carriage, said means being rendered effective by said traveling movements.

12. In a typewriting machine, the combination of a traveling carriage, a cutting element fixedly secured to said carriage, a second and coöperative cutting element pivotally supported on said carriage, and means 65 operating automatically to swing said sec-

ond element on its pivot toward and from the first recited cutting element, the paper being cut during such swing.

13. In a typewriting machine, the combination of a traveling carriage, a cutting element secured to said carriage, a second and coöperating cutting element pivotally supported on said carriage, and means operating automatically to swing said second element on its pivot toward and from the first recited cutting element, the paper being cut during such swinging movement, said means operating automatically during traveling movements of said carriage.

14. In a typewriting machine, the combination of a traveling carriage, a cutting element fixedly secured to said carriage, a second and coöperating cutting element pivotally supported on said carriage, and means operating automatically to swing said second element on its pivot toward and from the first recited cutting element, said means comprising a stationary device and a co-operating arm on said second cutting element.

15. In a typewriting machine, the combination of a traveling carriage, a cutting element fixedly secured to said carriage, a second and coöperating cutting element pivotally supported on said carriage, and means operating automatically to swing said second element on its pivot toward and from the first recited cutting element, said means comprising a stationary abutment coöperative with a projection on said second element to swing said second element toward the first element to cut the paper and further comprising spring means operative to swing said second element away from the first element and restore said second cutting element to normal position.

16. In a typewriting machine, the combination of a traveling carriage, a cutting blade rigid thereon, a coöperating cutting blade pivoted to a fixed pivot on said carriage, stop devices for limiting the pivotal movements of said pivoted blade, a spring connected with said pivoted blade for maintaining certain of said stop devices in engagement normally to determine the normal position of said pivoted blade, and means for overcoming said spring and swinging said pivoted blade to cause to co-act with the rigid blade to cut paper.

17. In a typewriting machine, the combination of a traveling carriage, a cutting blade rigid thereon, a coöperating cutting blade pivoted on said carriage, stops for limiting the pivotal movements of said pivoted blade, spring means connected with said pivoted blade for maintaining certain of said stops in engagement normally to determine the normal position of said pivoted blade, and means for overcoming said spring means and swinging said pivoted blade to

- cause it to co-act with the first recited blade to cut paper, said last named means comprising a projection or finger on said pivoted blade and a coöperating abutment fixed to 5 the frame of the machine.
18. In a typewriting machine, the combination of a traveling carriage, an operating cutting blade pivoted on said carriage, a device coöperative with said blade to effect 10 the cutting of the paper, stop devices for limiting the pivotal movements of said cutting blade, a spring connected with said cutting blade for maintaining certain of said stop devices in engagement normally to determine 15 the normal position of said cutting blade, and means for overcoming said spring and swinging said cutting blade to cause it to co-act with said device to cut paper, said last named means comprising a projection or 20 finger on said cutting blade, and a stationary arm provided with a stud projecting into the path of said finger or projection.
19. In a typewriting machine, the combination of a carriage, a cutting blade, a co- 25 operating cutting device, said blade being pivotally supported and provided with fingers projecting in opposite directions from its pivot, a coiled restoring spring connected to one of said fingers, an abutment co- 30 operating with the other finger to swing said blade automatically to co-act with said device, and stop devices for limiting the pivotal movements of said blade.
20. In a front-strike typewriting machine, 35 the combination of a traveling carriage, a platen thereon, a shearing blade pivotally supported above said platen, and means operating to swing said blade and give it a shearing stroke in a substantially horizontal 40 plane transverse of said platen.
21. In a front-strike typewriting machine, the combination of a platen carrier; a platen; a supporting bar on said carrier; means for securing said supporting bar at 45 variable heights in respect to the printing line on the platen, said means including posts having threaded portions over which said bar is fitted, and locking nuts on said portions, said nuts coöperating with the upper 50 and lower faces of said bar; and paper cutting devices mounted on said supporting bar.
22. In a front-strike typewriting machine, the combination of a traveling carriage, a platen thereon, a pivotally mounted shearing 55 blade arranged above said platen, and means operating to swing said blade on its pivot and give it a shearing stroke in a substantially horizontal plane, said means operating automatically during traveling movements of said carriage.
23. In a front-strike typewriting machine, the combination of a traveling carrier, a platen thereon, a cutting blade secured to said carrier above the platen, a movably 60 mounted cutting blade also arranged above said platen, and means operating automatically to move said movably mounted blade to and fro in a substantially horizontal plane, such movement in one direction causing it to coöperate with the first recited blade to 70 shear the paper that passes between them, movement of said cutting blade in the opposite direction carrying it out of operation.
24. In a front-strike typewriting machine, the combination of a carriage, a platen 75 thereon, a bar fixed to the carriage and extending longitudinally of the platen, said bar being arranged above and forward of the platen, a cutting blade fixed to said bar, a second cutting blade pivoted to said bar, 80 stop devices for said pivoted blade, a spring connected to said bar and to said pivoted blade and tending to maintain certain of said stop devices in normal coöperation, and means on the frame coöperative with a projection on the pivoted blade during traveling movements of the carriage to cause said blade to coöperate to cut paper.
25. In a front-strike typewriting machine, the combination of a carriage, a platen 90 thereon, a bar fixed to the carriage and extending longitudinally of the platen, said bar being arranged above and forward of the platen, a cutting blade fixed to said bar, a second cutting blade pivoted to said bar, 95 stop devices for said pivoted blade, a spring connected to said bar and to said pivoted blade and tending to maintain certain of said stop devices in normal coöperation, means for causing coöperation of said blades 100 during traveling movements of the carriage, and a guide secured to said bar and guiding the paper upward from the printing face of the platen and between said blades.
26. In a front-strike typewriting machine, 105 the combination of a carriage, a platen thereon, a bar fixed to the carriage and extending longitudinally of the platen, said bar being arranged above and forward of the platen, a cutting blade fixed to said bar, 110 a second cutting blade pivoted to said bar, stop devices for said pivoted blade, a spring connected to said bar and to said pivoted blade and tending to maintain certain of said stop devices in normal coöperation, means for causing coöperation of said blades 115 during traveling movements of the carriage, a guide secured to said bar and guiding the paper upward from the printing face of the platen and between said blades, a receptacle 120 for the severed portions of the paper, said receptacle being mounted on said bar, and means for moving the severed portions of the paper to said receptacle.
27. In a typewriting machine, the combination of paper shearing devices, and means operating automatically to move the portions of the paper that have been sheared to make way for the advanced portion of the unsheared paper.

28. In a typewriting machine, the combination of paper shearing means, a paper receiver, and means for moving the sheared portions of the paper to said receiver.
- 5 29. In a typewriting machine, the combination of a traveling carriage, paper shearing means, a paper receptacle, and means for moving the sheared portions of the paper to said receptacle, said means operating automatically during traveling movements of said carriage.
- 10 30. In a typewriting machine, the combination of two coöperating paper cutting elements, means operating automatically to effect relative movement of said elements to cut the paper that passes between them, and means operative concurrently with said last named means for moving the paper out of the way after it has been cut.
- 15 31. In a typewriting machine, the combination of two coöperating paper cutting elements, means operating automatically to effect relative movement of said elements to cut the paper that passes between them, and means connected with one of said cutting elements and operative automatically thereby to move the cut portions of the paper out of the way.
- 20 32. In a typewriting machine, the combination of a traveling carriage, two relatively movable paper shearing elements both mounted on said carriage, means operative automatically during the carriage travel to cause said elements to coöperate to shear the paper, and means connected with said elements and operative thereby to move the sheared portions of the paper to one side, out of the way.
- 25 33. In a typewriting machine, the combination of two pivotally connected cutting blades, means for causing said blades to co-operate to cut paper that passes between them, and an abutment mounted on one of said blades and operative automatically to move the cut portions of the paper to one side.
- 30 34. In a typewriting machine, the combination of two pivotally connected cutting blades, means for causing said blades to co-operate to cut paper that passes between them, a paper receptacle, and an abutment connected to one of said blades and operative to move the cut portions of the paper to said receptacle.
- 35 35. In a typewriting machine, the combination of a traveling carriage, a cutting blade secured thereon, a coöperating cutting blade pivotally mounted on said carriage, and an abutment or plate mounted on said pivoted blade and operative concurrently with the cutting operation to move the cut portions of the paper to one side.
- 40 36. In a typewriting machine, the combination of a traveling carriage, a paper supply roller thereon arranged at the introductory side of the platen, paper cutting devices arranged at the delivery side of the platen, a support for said supply roller adjustable lengthwise of the platen, and paper guiding devices between said roller and said cutting devices, said paper guiding devices including a guide bar having marginal guides for the paper, said guide bar being mounted on said support and adjustable relatively thereon lengthwise of said platen.
- 45 37. In a typewriting machine, the combination of a traveling carriage, a platen thereon, line spacing devices for the platen including a handle that is operative also to restore the carriage from left to right, paper cutting devices on the carriage, and means operating at a predetermined point in the return travel of the carriage to cause said devices to cut the paper.
- 50 38. In a typewriting machine, the combination of a traveling carriage, relatively movable paper shearing elements, and means operative automatically at a predetermined point in the travel of the carriage to cause said devices to coöperate to cut the paper.
- 55 39. In a typewriting machine, the combination of a traveling carriage, two relatively movable paper shearing elements both mounted on said carriage, and means operative automatically to effect relative movements between said elements to sever the paper, said means operating automatically at a predetermined point during return movements of said carriage.
- 60 40. In a typewriting machine, the combination of a carriage, paper severing devices, a paper receiver, means for moving the severed paper to said receiver, said devices, receiver and means all being mounted on the carriage, and relatively stationary means for operating said devices and actuating said moving means.

Signed at the borough of Manhattan, city of New York, in the county of New York, and State of New York, this 28th day of April, A. D. 1913.
